CAR ARTICULATION

William H. Mussey and Martin P. Blomberg, Chicago, Ill., assignors to Pullman-Standard Car Manufacturing Company, Chicago, Ill., a corporation of Delaware

Application March 26, 1934, Serial No. 717,416

5 Claims. (Cl. 105—4)

This invention relates to cars of the type sometimes called articulated cars, and which comprise two or more sections having separate car bodies with adjacent ends articulated to and carried by a common truck. And the principal objects of the invention are to provide great strength and security with free jointed or articular movement of the range required for railway service and to simplify the end sill and center plate structures.

Further objects and advantages will appear as the disclosure proceeds and the description is read in connection with the accompanying drawing in which

15 Fig. 1 is a perspective view with the several parts slightly displaced and one end sill broken away to better show the general forms and relations of parts;

20 Fig. 2 is a more complete perspective view of the end sill broken away in Fig. 1;

Fig. 3 is a longitudinal, vertical section along the center line of the car.

However, the specific form shown and described is intended for illustration only.

25 Swing motion trucks are generally preferred for articulated cars (Car Builders' Cyclopedia, 1931, pp. 83, 569, 580) but that is a matter of selection from various types (Ibid., section 10, pp. 763 to 791).

30 The common truck is here represented by a bolster 10 and the car bodies by end sills 11 and 12. The bolster 10 carries a truck center bearing plate 13, having a pintle 14 surrounded by a concave bearing surface 15.

35 The end sill 12 is equipped with a body center plate bracket, generally indicated at 16 (Fig. 1), which bears the body center plate 17 (Fig. 3), having an opening 18 to receive the pintle 14, and presenting a convex bearing surface 19 towards the truck center bearing surface 15 and a concave bearing surface 20 upwardly.

40 The end sill 11 is equipped with a similar body center plate bracket, generally indicated at 21, (Fig. 1) which bears a center plate 22 (Fig. 3) having a bearing portion 23 and an opening 24 for the pintle 14 and presenting a convex bearing surface 25 to the surface 20 of the body center plate 17.

45 The body center plate 17 has a downwardly directed flange 26 forming a sort of protecting skirt for the truck center plate, and an upwardly directed flange 29, which has a cylindrical inner surface 30, receiving a corresponding portion 31 of the body center plate 22.

50 The actual bearing surfaces of the center plates

are separated by antifriction or self-lubricating material 32, preferably of that type comprising porous metal charged with lubricant, and thereby providing self-lubricating bearings.

The flange 29 of the center plate 17 merges 5 into side faces 33 (Fig. 1) of considerable vertical width, and they all join what may be called the body portion of the center plate bracket 16, which has an upper face machined in steps 34 and 35. The lower step 34 has a transverse key groove 36 10 and the upper step has a stout dowel 37.

The end sill 12 has, on its lower side, a machined face in steps 38 and 39, corresponding to the steps 34 and 35. The step 38 has a key groove 40 opposite to the key groove 36, and receiving 15 with it a key 41. The end sill also has a vertical pocket or bore 42 opening through the step 39, and receiving the dowel 37.

The body center plate bracket 21 has a machined upper face 43 and a stout dowel 44 which 20 cooperates with a machined face 45 and a pocket or bore 46 of the end sill 11, all as best shown in Fig. 3. A key 47 corresponding to the key 41 traverses the joint between the faces 43 and 45.

The respective end sills and body center plate 25 brackets are made fast by bolts 48. It will be observed, however, that the form and arrangement of the several parts relieves the bolts of practically all duty except that of mere fastenings.

The holes 42 and 46 for the dowels are formed 30 in corresponding heads 49 and 50 on the respective end sills, which are ordinarily separated, as best shown in Fig. 3, by about three-eighths of an inch in this selected embodiment.

The bearing surfaces of the truck and body 35 center plates are substantially spherical in form, and will, therefore, allow the truck and the respective car bodies to have jointed or swinging movements relative to each other in all directions 40 as the car passes over curved pieces of track having the outer side higher than the inner side, or as it passes over curves in vertical planes relative to the surface of the earth.

There are no side bearings between the end 45 sills and the bolster 10. Instead, the end sills have arms 51 and 52 pivoted to links 53 which, in turn, are pivotally and resiliently connected to the end portions 54 of the bolster 10 by some means specifically unimportant here.

50 By slightly modifying the inner center plate bracket 21, the end sill casting 11 may be made identical with the end sill casting 12. Such a modification would merely entail the provision of a step similar to the one indicated at 39 on the outer center plate bracket 16 and increasing the 55

height of the bracket so that the dowel 44 will properly engage the opening 46 in the head 49.

Preferably the pintle 14 is hollow so that a center pin may be used if desired.

5 We claim—

1. In a car, a body center plate bracket presenting a dowel and a joint face upwardly, an end sill presenting a corresponding face downwardly and having an opening for the dowel, and

10 a center plate on the bracket presenting top and bottom bearing faces, the dowel being substantially over the bearing faces.

2. In a car, a truck bolster adapted to support adjacent ends of two car bodies, a truck center plate, car body center plates resting one above the other on the truck center plate, the intermediate center plate having an upwardly extending flange engaging the periphery of the top center plate, a downwardly projecting skirt protecting the bearing surface between the two lower plates, and means for attaching said body center plates to adjacent ends of car bodies.

3. In a car, a body center plate bracket having an integral stout dowel extending upwardly therefrom and a stepped face on its upper surface, an end sill resting on said face and having an opening receiving the dowel, said bracket having a bearing portion extending outwardly beyond said dowel forming a convex bearing surface on its lower side and a concave bearing surface on its upper side, said bearing portion having an opening therethrough, and vertical flanges extending upwardly and downwardly about the peripheries of said bearing surfaces, respectively.

35 4. In a car, a body center plate bracket presenting a dowel and a joint face upwardly and a center plate on the bracket presenting a convex

bearing face downwardly and a concave bearing face upwardly, said center plate having a flange extending vertically upwardly about the periphery of said concave bearing face and a flange extending vertically downwardly about said convex bearing face adjacent to the periphery thereof for protecting said bearings against the entrance of foreign matter.

5 5. In an articulated train, a pair of adjacent car sections, means for connecting said sections together and for supporting the same comprising a car end sill on each section, a body center plate bracket for each section, each bracket having an inwardly extending portion, an outwardly extending portion and an intermediate upwardly extending portion, said inwardly extending portions extending beneath the corresponding sills, each inwardly extending portion and the under side of the adjacent sill having oppositely facing shoulders spaced apart in parallel vertical planes, thus forming a pair of adjacent shoulders, a key rectangular in cross section engaging each adjacent pair of shoulders, vertically extending bolts for holding said brackets in engagement with said sills whereby said shoulders and keys will relieve said bolts of stresses due to draft forces applied to said brackets, said upwardly extending portions extending upwardly alongside and in contact with the outer portions of said sills for relieving said bolts of shearing stress due to buffering forces and cooperating with said keys for resisting upwardly directed turning forces applied to the outer ends of said brackets, and concentric bearings on the outer portions of said brackets for supporting said car sections on a truck.

MARTIN P. BLOMBERG.
WILLIAM H. MUSSEY.
